LAUNDRY SHAKE-OUT TUMBLER

Edward D. Purkett, Joplin, Mo., assignor to
Purkett Laundry Company, Joplin, Mo.

Application March 22, 1933, Serial No. 662,159

5 Claims. (Cl. 259—29)

This invention relates to laundry shake-out tumblers.

It is the common practice in laundries to twist or wring articles such as towels, sheets, etc., after 5 they have been laundered, until nearly dry. The articles thus twisted are subjected to rather severe shaking to loosen them up preparatory to feeding them to the ironers.

An important object of the present invention is 10 to provide a novel shake-out tumbler which is operative for loosening up or shaking out clothes of the character referred to and for delivering them from the apparatus ready for ironing.

A further object is to provide a shake-out tumbler which is normally operative in a pre- 15 determined position for receiving laundered articles which are to be loosened or shaken, and which is adapted to be substantially inverted after the shaking action is completed to discharge 20 the articles therefrom without handling, preparatory to feeding the articles to the ironers.

A further object is to provide an apparatus 25 of the character referred to wherein the tumbler moves bodily from its loading to its unloading position to facilitate the transferring of the articles from the loading point to the tables usually arranged adjacent the ironing machines.

A further object is to provide a shake-out tumbler which is adapted to be simultaneously 30 rotated from its loading position to its unloading position and moved bodily to a suitable discharge point, and wherein such simultaneous operations are effected by the operation of a single wheel or similar operating element.

A further object is to provide a shake-out tumbler of the character indicated wherein the axis 35 of revolution of the tumbler is located substantially in the vertical plane of the center of gravity to permit the tumbler to be moved to its discharging position with minimum effort on the part of the operator.

Other objects and advantages of the invention will become apparent during the course of the following description.

In the drawings I have shown one embodiment 45 of the invention. In this showing,

Figure 1 is a side elevation,

Figure 2 is a front elevation,

Figure 3 is a plan view,

Figure 4 is an enlarged fragmentary vertical 50 sectional view on line 4—4 of Figure 3, and

Figure 5 is a similar view on line 5—5 of Figure 3.

Referring to Figures 1 and 2, the numeral 10 55 designates a table as a whole comprising lower

substantially horizontal supports 11 which may be formed of angle iron as shown, and these supports are preferably provided with adjusting screws 12 forming the legs of the table. These screws operate to vary the height of the table as desired within reasonable limits. Upstanding pedestals 13 are connected at their lower ends to the supports 11 and are secured at their upper ends to horizontal supporting arms 14. These arms also may be formed of angle iron as indicated in Figure 2. The pedestals 13 are preferably angularly braced as at 15 and horizontally braced as at 16.

Each of the arms 14 is provided on its upper face with a rack 17 secured thereto in any suitable manner. Axially aligned gears 18 mesh with the racks 17, and each of these gears is keyed or otherwise secured to a stub-shaft 19. Each of the stub-shafts is preferably provided at its outer end with an operating wheel 20, but it will 20 become apparent that only one of these wheels is necessary, and that any other suitable type of means for rotating the shafts 19 may be employed.

A substantially U-shaped frame 21 is arranged 25 between the gears 18 and may be formed of channel iron or other suitable material in order that it may possess the desired rigidity. The arms of the frame 21 are arranged parallel to the arms or rails 14 and are provided with outer spacing collars 22 within which the stub-shafts 30 19 are secured. The frame 21 includes a transverse member 23 to which is secured a bearing 24, as shown in Figure 4, for a purpose to be described.

A tumbling drum 25 is arranged within the 35 frame 21, as shown. This drum includes a bottom 26 and substantially cylindrical side walls 27, and the top of the drum is formed substantially conical as at 28 with a relatively large central opening 29 therethrough for the insertion of clothes in a manner to be described. A stub-shaft 30 is secured to the bottom 26 of the tumbler and projects through the bearing 24, a retaining nut 31 being arranged on the end of the stub-shaft. It 40 will be apparent that any suitable form of anti-friction bearings may be employed within the bearing 24.

A motor 32 is secured to one side of the frame 21 and is provided with a pulley 33 around which 50 passes an endless driving belt 34. This belt passes around the cylindrical portion of the tumbler, as clearly shown in Figure 5, and an idler pulley 35 preferably is employed for tensioning the belt 34. This pulley is urged upwardly by springs 36, and 55

is supported by bearings 37 mounted upon a bracket 38.

The apparatus is particularly intended for use with a standard laundry ironer (not shown) and such machine ordinarily is provided with a rotating feeding table as indicated by the numeral 39. As will become apparent, the clothes are discharged upon this table after they have been suitably loosened or shaken out.

10 The operation of the apparatus is as follows:

The tumbler 25 normally occupies the position shown in solid lines in Figures 1 and 4. The motor 32 preferably operates constantly, and the relative sizes of the pulley 33 and the cylindrical portion of the tumbler are such as to provide the desired speed reduction in the rotation of the tumbler. Clothes are fed into the opening 29 as the tumbler rotates, and the axis of the supporting spindles or stub-shafts 19 preferably is in the vertical plane of the center of gravity of the tumbler and the parts connected thereto whereby the tumbler operates when either loaded or unloaded without any tendency to rotate about the axis of the spindles 19.

25 The rotation of the tumbler 27 about the axis of the shaft 39 continues until the clothes have been suitably loosened. In this connection it will be noted that the rotation of the tumbler continually elevates and then drops the clothes to tend to loosen them substantially in the same manner that they are conventionally loosened by shaking with the hands. When the loosening operation has been sufficiently completed, it merely is necessary for the operator to rotate one of the wheels 20, and this operation may be accomplished with little physical effort in view of the placing of the spindles 19 with respect to the tumbler. The rotation of one of the wheels 20 in a counterclockwise direction as viewed in Figures 40 1 and 4 causes the tumbler to be rotated about the axis of the spindles 19, and the action referred to also rolls the gears 18 along the racks 17. The gear and rack arrangements at opposite sides of the apparatus are identical, and accordingly the 45 axis of rotation of the spindles 19 partakes of no angular change.

The rotation of one of the wheels 20 is continued until the tumbler assumes substantially the dotted line positions shown in Figures 1 and 50 4 at which point the tumbler is substantially inverted and the opening 29 is arranged substantially vertically beneath the uppermost portions of the tumbler. During the entire operation referred to, the tumbler is rotated by the motor 32, 55 and this rotation, when the tumbler reaches discharging position, continues to elevate the clothes after which they progressively drop through the opening 29 in a loosened condition upon the table 39. As soon as the tumbler is completely emptied 60 one of the wheels 20 is again rotated in the opposite direction to restore the parts to normal position ready to be loaded with twisted clothing. The operators of the ironing machines are thus supplied with damp loosened articles upon the 65 table 39, and these articles are picked up and fed into the ironers in the usual manner without the necessity of having to loosen or shake out the articles. Thus the manual labor ordinarily involved in the shaking out of the articles is completely avoided, the tumbler performing this work in a quick efficient manner.

The use of the apparatus has further advantages for the reason that it permits the feeding of the clothes to the apparatus from one side 70 thereof while the clothes are discharged from the

other side of the apparatus to the receiving table. Thus the operators who feed the clothing into the tumbler do not interfere in any way with the operators who pick up the articles from the table 39 and feed them to the ironing machine.

5 Wheels 20 preferably are provided at both sides of the apparatus merely as a matter of convenience, but it will be apparent that only one wheel need be employed. Moreover, a lever or similar operating element may be employed in place of the wheel. It further will be obvious that the length of the racks 17 and the diameters of the gears 18 may be varied as desired according to the distance through which it is desired to move the tumbler bodily from its loading to its unloading 15 position.

It is to be understood that the form of my invention herewith shown and described is to be taken as a preferred example of the same and that various changes in the shape, size, and arrangement of parts may be resorted to without departing from the spirit of the invention or the scope of the subjoined claims.

I claim:

1. Apparatus of the character described comprising a supporting frame, a substantially cylindrical tumbler having its axis normally arranged substantially horizontally, said tumbler having an opening in one end, a shaft connected to the other end of said tumbler and journaled in said frame, 30 a motor supported by said frame and having a pulley arranged with its axis parallel to the axis of said tumbler, and an endless belt passing around said pulley and around said tumbler, means for supporting said frame for rotation 35 about a horizontal axis, and means for effecting bodily movement of said frame at right angles to said horizontal axis during rotation of the frame thereabout.

2. Apparatus of the character described comprising a supporting frame, a substantially cylindrical tumbler having its axis normally arranged substantially horizontally, said tumbler having an opening in one end, a shaft connected to the other end of said tumbler and journaled in said frame, 40 a motor supported by said frame and having a pulley arranged with its axis parallel to the axis of said tumbler, and an endless belt passing around said pulley and around said tumbler, and means for supporting said frame for simultaneous 45 rotation about a horizontal axis and for bodily movement substantially horizontally at right angles to such axis.

3. Apparatus of the character described comprising a normally horizontal substantially U- 55 shaped frame, a substantially cylindrical shake-out tumbler having an opening in one end and having its axis normally substantially horizontal, a shaft connected to said tumbler coaxially thereof and rotatably connected to said frame, a pair 60 of horizontal stationary racks arranged adjacent opposite sides of said frame, and coaxial gears carried by said frame and meshing with said racks.

4. Apparatus of the character described comprising a supporting frame, a substantially cylindrical shake-out tumbler connected to said frame for rotation about its axis, a motor carried by said frame and having a pulley arranged with its axis parallel to the axis of said tumbler, an end- 70 less belt passing around said pulley and said tumbler, a pair of supporting racks, and a pair of coaxial gears carried by said frame and meshing with said racks.

5. Apparatus of the character described com- 75

prising a normally horizontal substantially U-shaped frame, a substantially cylindrical shake-out tumbler having its axis normally substantially horizontal, a shaft connected to said tumbler co-
5 axially thereof and rotatably connected to said frame, a motor rigidly connected to said frame and provided with a pulley arranged with its axis

parallel to the axis of said tumbler, an endless belt passing around said pulley and around said tumbler, a pair of racks arranged adjacent opposite sides of said frame, and coaxial gears carried by said frame and meshing with said racks.

5

EDWARD D. PURKETT.
